BY MESNE ASSIGNMENTS, TO ROTH MANUFACTURING COMPANY, OF CHICAGO,
ILLINOIS, A CORPORATION OF ILLINOIS.

HOSE-COUPING.

1,346,423.

Specification of Letters Patent.

Patented July 13, 1920.

Original application filed January 24, 1916, Serial No. 73,885. Divided and this application filed April 10, 1919. Serial No. 288,903.

To all whom it may concern:

Be it known that we, EDWARD A. RUSSELL and SEELYE P. HARRIMAN, citizens of the United States, residing at Chicago, in the county of Cook and State of Illinois, have invented certain new and useful Improvements in Hose-Couplings of which the following is a specification.

Our invention relates to hose couplings, particularly to couplings for connecting the hose or equivalent elements in the steam train lines on railway cars.

The principal object of the invention is to provide a hose coupling, of simple construction and of the straight port type, suitable for use in this connection, by means of which the coupling and uncoupling operations may be effected without the rocking movement of the coupler elements characteristic of the "Sewall" or gravity type of couplers, such rocking movements being objectionable because necessitating a bending of the hose, and also because, by rocking the coupler elements with the gaskets in contact, the engaging faces of the latter are likely to be crushed, frayed, or otherwise injured.

A further object of the invention is to provide a coupler so constructed that the gaskets will be brought into close and accurate contact with each other to provide a steam tight joint even when one or both of the gaskets have shrunk or, for other reasons, are shorter than they are intended to be.

35 A further object is to provide a coupling in which the gaskets may be separated when desired to permit the discharge of water or condensation from the train line without requiring the couplers themselves to be disconnected, one from the other.

40 A further object is to provide a coupler having the characteristics above noted, which can be mated with any of the standard gravity straight port couplers now in use on railroads, couplers of this class being all much alike but differing in certain respects as to details of construction.

45 A further object is to provide a coupler adapted to be positively locked with the mating coupler element without the employment of any of the special locks such as are now in use on many steam train pipe couplers.

The invention consists of the novel and improved constructions, arrangements and devices, to be hereinafter described and claimed, for carrying out the above stated objects, and such other objects as will appear from the following description.

55 This application is a division of our co-pending application, Serial No. 73,885, filed January 24, 1916.

Our invention is illustrated in a certain preferred embodiment in the accompanying drawings, wherein

65 Figure 1 is a side elevational view of a coupler embodying our invention.

Fig. 2 is an enlarged plan view of the two coupler heads, showing them in the position they assume just before being brought into coupled relationship; and

70 Fig. 3 is a longitudinal sectional view taken along the line 3—3 of Fig. 2.

75 Like characters of reference designate like parts in the several figures of the drawings.

As the two elements of the coupler are exactly alike, we will describe the left-hand element by the use of reference numerals, with the understanding that the corresponding parts of the other element are indicated on the drawing by corresponding numerals distinguished by the exponent letter "a".

80 The coupling member or head 10 is formed preferably with the usual projecting locking arm 11 provided with an undercut cam lug 12. On the other side of the coupling member is an undercut cam lug 13. These lugs, or as they may be called, gravity cams, engage with the corresponding cam lugs on the mating coupler arm 11^a. Preferably the coupling members are provided with means whereby they will be held in proper alignment before the gaskets are moved into contact with each other, and subsequently as against any tendency there may be for the members to rock on their cams when force is applied to the gasket holding or conduit members for the purpose of bringing the gaskets together. With

85 90 95 100 105 these ends in view, the undercut groove 14 in the arm 11 is closed at the bottom as indicated at 14', forming a stop for the interlocking lug 13^a of the mating coupler member. This prevents the coupling members from being rocked when the gaskets

are pressed together so as to produce a gap between the gaskets at the top; such tendency being due to the arrangement of the locking lug centers below the axis of the 5 gaskets. The lug 13 is formed on the top with a projection 13' and the arm 11^a of the other coupler member is provided with a stud 15^a which bears against this projection. This arrangement prevents the weight 10 of the coupling members from producing a gap between the gaskets at the bottom and holds the coupling members in alignment with each other before the gaskets are in contact. The arrangement also permits the 15 coupling up of either coupling member with any standard coupler head of the gravity type. The reason for forming the lug 13 with the projection 13' instead of placing the stud 15^a lower is to permit the coupling up of either coupling member with any standard coupler head of the gravity type. In such cases the stud clears the locking 20 lug of the mating head.

The coupling member 10 is hollow, being 25 formed with a cylindrical bore 16, the bore being enlarged at the coupling end to form a shoulder 17 against which the head of the gasket holder 18 may abut when the gasket holder is in the innermost position. The 30 gasket holder or conduit member 18 is cylindrical and projects through the coupling member 10, and is preferably threaded at 19 to receive the usual hose nipple. Commencing at the end of the threads 19 the gasket 35 holder 18 is preferably provided with a plurality of somewhat coarse threads 20 with which the nut or actuating member 21 is engaged, as clearly shown in Fig. 3. The actuating member 21 is rotatably connected 40 to the coupling member 10 by means of a plurality of longitudinally projecting fingers on studs 22 which extend out over the coupling member 10, the ends of the studs being bent over at substantially right angles 45 and projecting into a groove 23 formed in the coupling member 10. For convenience in turning the actuating member 21 may be provided with a handle 24. The forward end of the gasket holder is formed with a 50 semi-circular flange 25, and is formed internally with a groove 26 to receive the gasket 27. The gasket is held in place in the gasket holder for all normal positions of the latter by an overhanging lug 28 on the 55 member 10. The gasket holder is provided with a lug 29 which extends between guide ribs 30 on the inner surface of the locking arm 11 to prevent rotation of the gasket holder. 60 Operation: The two coupling members are brought together in the manner shown in Fig. 2, that is, moving them sidewise, without rocking one toward the other, the gasket holders 18 and 18^a being retracted, 65 that is, in their innermost position. The fact

that the gasket holders are retracted allows the locking arms 11 and 11^a of the coupling members to clear the corresponding locking lugs 13, 13^a, and it is for this reason that it is not necessary to rock the coupling members. 70 In the coupling operation they need not be shifted out of parallelism with each other. As soon as the coupling members are brought together, they may be released and will then interlock in what may be termed a 75 preliminary interlocking engagement, which is brought about by gravity, the cams operating to center the gasket holding or coupling members and holding them centered against accidental displacement or against 80 disturbance when the gaskets are forced against each other. The coupling members are held against rocking on their cams by the studs 15, 15^a bearing on the projections 13' and 13^a. After the heads have been 85 thus engaged, the gasket holders are pushed forward, each in the direction toward the other, by giving partial rotation to the actuating members 21 and 21^a. The gaskets move along a line normal to their meeting 90 faces, so that the latter come together squarely. There is enough looseness between the gasket holders and the coupling members and between the gaskets and the gasket holders so that the meeting faces of 95 the gaskets will adjust themselves to each other regardless of possible slight inequalities on the castings forming the coupling members. It will be seen that when the coupling members have been preliminarily 100 engaged they will hang in substantially normal position and need not be held by the trainman whose hands are free to operate the actuating members 21, 21^a. Any tendency of the actuating members, when pressure is applied, to rock the coupling members on each other so as to prevent a flat bearing of one gasket on the other, impairing the tightness of the joint and injuring 105 the gaskets, is checked by the engagements 110 of the shoulders 14' and 14^a with the cams on which they bear and by the engagement of the studs 15, 15^a with the projections 13', 13^a. When the coupling member is disengaged, the gasket may be removed from the 115 gasket holder by forcing the gasket holder forward far enough so that the gasket will clear the lug 28.

The parts are assembled as follows: The studs 22 of the actuating member 21 are 120 slipped into the groove 23 of the coupling member 10 from one side and the actuating member brought into alignment with the bore of the coupling member. The gasket holder is thrust into the coupling member 125 and threaded through the actuating member 21. After the threads 20 engage the actuating member is rotated until the forward end of the gasket holder is flush with the forward end of the lug 28. A gasket may then 130

be placed in the holder and the actuating member rotated to bring the gasket holder back against the shoulder 17 with the lug 28 in the slot in the coupling member.

5 While we have described our invention in a preferred embodiment, it will be understood that further modifications might be made without departure from the principles of the invention. Therefore we do not 10 wish to be understood as limiting the invention to the particular constructions, arrangements and devices shown and described, except so far as the claims are expressly so limited.

15 We claim:

1. A hose coupler comprising in combination a coupling member and a conduit member movable longitudinally through the coupling member, the latter being provided with means whereby it may be preliminarily engaged with a mating coupler and held in substantially normal alinement therewith, and a device for producing relative longitudinal movements between said 20 coupling and conduit members to seat the latter against the mating coupler comprising a rotatable element having a threaded connection with one of said members and provided with means engaging the other 25 of said members.

2. A hose coupler comprising in combination a coupling member and a conduit member movable longitudinally through the coupling member, the latter being provided with means whereby it may be preliminarily engaged with a mating coupler and held in substantially normal alinement therewith, and a device for providing relative longitudinal movements between said 35 coupling and conduit members to seat the latter against the mating coupler comprising a rotatable element having a threaded connection with the conduit member and provided with means engaging the coupling 40 member.

3. A hose coupler comprising in combination a coupling member and a conduit member movable longitudinally through the coupling member, the latter being provided with means whereby it may be preliminarily engaged with a mating coupler and held in substantially normal alinement therewith, and a device for producing relative longitudinal movements between said 55 coupling and conduit members to seat the latter against the mating coupler comprising a rotatable element having a threaded connection with one of said members and provided with a finger engaging a groove in the other member.

4. A hose coupler comprising in combination a coupling member and a conduit member movable longitudinally through the coupling member, the latter being provided 60 with means whereby it may be preliminarily

rily engaged with a mating coupler and held in substantially normal alinement therewith and a device for providing relative longitudinal movements between said coupling and conduit members to seat the latter against the mating coupler comprising a rotatable element having a threaded connection with the conduit members and provided with a finger engaging a groove in the coupling member. 70

5. A hose coupler comprising in combination a coupling member and a conduit member movable longitudinally through the coupling member the latter being provided with means whereby it may be preliminarily engaged with a mating coupler, by lateral movement of said coupling member and other coupler without rocking the same, and held in substantially normal alinement therewith, and a device for producing relative longitudinal movement between said coupling and conduit members to seat the latter against the mating coupler comprising a rotatable element having a threaded connection with one of said members and provided with means engaging the other of said members. 75

6. A hose coupler comprising in combination a coupling member and a conduit member movable longitudinally through the coupling member, the latter being provided with means whereby it may be preliminarily engaged with a mating coupler of the gravity or Sewall type and held in substantially normal alinement therewith, and a device providing relative longitudinal movement between said coupling and conduit members to seat the latter against the mating coupler comprising a rotatable element having a threaded connection with one of said members and provided with means engaging the other of said members. 95

7. A hose coupler comprising in combination a coupling member and a conduit member movable longitudinally through the coupling member, the latter being provided with means whereby it may be preliminarily engaged with a mating coupler by lateral movement of said coupling member and other coupler without rocking the same, and a device for producing relative longitudinal movement between said coupling and conduit members to seat the latter against the mating coupler, comprising a rotatable element having a threaded connection with one of said members and provided with means engaging the other of said members. 100

8. A hose coupler comprising in combination a coupling member and a conduit member movable longitudinally through the coupling member, the latter being provided with means whereby it may be preliminarily engaged with a mating coupler of the gravity or Sewall type by lateral movement of said coupling member 110

- and other couplers without rocking the same and a device for producing relative longitudinal movement between said coupling and conduit members to seat the latter against the mating coupler comprising a rotatable element having a threaded connection with the conduit member and a stud and groove connection with the coupling member.
- 5 10. A hose coupler comprising in combination a coupling member and a conduit member movable longitudinally through the coupling member, the latter comprising a head having a curved undercut locking jam lug on one side thereof and an arm projecting from the other side having a cam to engage a locking jam lug on the mating coupler, means whereby the coupling member may be preliminarily engaged with a mating coupler and held in substantially normal alinement therewith, and a device for
- 15 20

producing relative longitudinal movements between said coupling and conduit member to seat the latter against the mating coupler comprising a rotatable element having a 25 threaded connection with the conduit member and a stud and groove connection with the coupling member.

10. A hose coupler comprising, in combination, a coupling member and a conduit member movable longitudinally through the coupling member, the latter being provided with means whereby it may be preliminarily engaged with a mating coupler and held in substantially normal alinement therewith, 35 and means for seating the conduit member against the mating coupler comprising a threaded nut, the movement of which produces a relative longitudinal movement between said coupling and conduit members. 40
